Primary Examiner—Robert M. Spear

(57) **CLAIM**

The ornamental design for an airplane tire, as shown and described.

DESCRIPTION

FIG. 1 is a right side elevational view of the airplane tire of the present invention, the left side elevational view being a mirror image thereof;

FIG. 2 is a front elevational view of the airplane tire of FIG. 1;

FIG. 3 is a rear elevational view of the airplane tire of FIG. 1;

FIG. 4 is a top plan view of the airplane tire of FIG. 1; and, FIG. 5 is a bottom plan view of the airplane tire of FIG. 1.
